UNITED STATES PATENT OFFICE.

DE LOSS H. STEPHENS, OF RIVERTON, CONNECTICUT.

ROTARY FILING-MACHINE.

SPECIFICATION forming part of Letters Patent No. 279,108, dated June 5, 1883.

Application filed February 5, 1883. (No model.)

To all whom it may concern:

Be it known that I, DE LOSS H. STEPHENS, of Riverton, in the county of Litchfield and State of Connecticut, have invented a new and Improved Rotary Filing-Machine, of which the following is a full, clear, and exact description.

The object of the invention is to make a uniformly smooth surface on metallic rules or similar articles, as hereinafter described.

Reference is to be had to the accompanying drawings, forming part of this specification, in which similar letters of reference indicate corresponding parts in all the figures.

Figure 1 is a side elevation of my improved machine. Fig. 2 is a plan view of the same; and Fig. 3 is a face view of the wheel, showing the position of the slide or carriage.

Upon a suitable stand or table, A, is a horizontal shaft, a, sustained in pillow-blocks b, and carrying at one end a circular disk or wheel, B, which is formed upon its face and near its edge with a roughened surface of suitable character. A standard, c, on bed A carries at its upper end a horizontal slideway, d, and upon this slideway a slide or carriage, D, is sustained. This construction gives a long and solid bearing to the carriage, so that vibration is prevented. At its end next the wheel the carriage is provided with a frame, E, formed to inclose the upper part of the wheel, and at the side next to the front face of the wheel the frame is formed with a vertical flange for carrying the rule against the wheel. The carriage is fitted for endwise movement by means of a treadle, f, and levers g. The wheel B is to be revolved at moderate speed by power applied to its shaft in any suitable manner. The rules are placed upon the carriage in different positions, according to whether they are to be reduced their entire length or for filing only the surface of the joint.

In Figs. 1 and 3 a rule, i, is shown as placed in position for reducing the surface the whole length, and in Fig. 2 a half-rule is shown as placed for filing the side of the main joint. The part e of the carriage has at the bottom a rib on which the rule is supported, and at the end a stop, which prevents the rule from being carried off the bed. The work being put in position, the operator moves the carriage back by pressing upon the treadle f, thus carrying the rule against the wheel.

It will be observed that the supports of the carriage are behind the wheel, while the frame on which the rule is placed is in front of the wheel. This enables the operator to stand closely by the machine while operating the treadle.

The location of the slide and frame being at the outer edge of the wheel, the joint to be filed is carried against the wheel, where the cut will be made in lines nearly parallel with the sides of the rule, thereby making nearly straight work on the surface of the joint.

The carriage and frame may be placed either horizontally or vertically. I do not limit myself in that respect, nor to the other details of construction exactly as described.

Having thus described my invention, what I claim as new, and desire to secure by Letters Patent, is—

In a rotary filing-machine, the combination, with the filing-wheel B and the sliding carriage D, of a frame, E, attached to the carriage, inclosing the wheel, and provided with a vertical flange, e, said flange being constructed to support the rule, substantially as described.

DE LOSS H. STEPHENS.
